INKING ARRANGEMENT FOR ROTARY PRINTING PRESSES

William N. Misuraca, Merrick, N. Y., assignor to
General Printing Ink Corporation, a corporation
of Delaware

Application March 18, 1937, Serial No. 131,590

9 Claims. (Cl. 101—350)

My invention relates to an improved inking arrangement for a rotary printing press.

In accordance with an important phase of my invention, the ink to be used in the printing operation is transferred in a novel and advantageous manner from the fountain roller of the printing press to an ink-distributing roller included in the mechanism of said printing press.

In accordance with another important phase 10 of my invention, an auxiliary roller positioned adjacent the fountain roller is so controlled that it may be utilized or left idle at will when transferring ink from the fountain roller to the afore- said ink-distributing roller.

Various other objects, advantages and characteristics of my invention will become apparent 15 from the following detailed description.

For an understanding of my invention and for an illustration of one of the forms thereof, reference is to be had to the accompanying drawings, in which:

Figure 1 is an elevational view showing the inking arrangement of my invention;

Fig. 2 is an elevational view of the arrangement shown in Fig. 1;

Fig. 3 is a fragmentary sectional view, partly in elevation, showing a part of the mechanism of Figs. 1 and 2;

Fig. 4 is an enlarged, longitudinal sectional view, partly in elevation, showing the inking arrangement of my invention;

Fig. 5 is an enlarged elevational view, partly in section, showing a different position of some of the operating parts; and

Figs. 6 and 7 are schematic views illustrating features of my invention.

Referring to the drawings, F and F₁ represent the side frames of the printing press, these side frames, as well understood in the art, serving as the support for the various cylinders, rollers, etc. forming the operating parts of said printing press. As indicated in Figs. 1 and 4, the side frames F, F₁ comprise the respective frame extensions f, f₁ utilizable as hereinafter described, these frame extensions being in alignment transversely of the machine.

It shall be understood that the printing press may be one which comprises the usual impression and blanket cylinders, not shown. Disposed 50 above the blanket cylinder is a plate cylinder 1 with which the usual form rollers 2 cooperate, sets of the rollers 2 being engaged by the respective rider rollers 3.

Disposed above the plate cylinder 1 is the 55 usual ink drum 4 with which, on the respective

opposite sides thereof, the intermediate rollers 5 are coactable, these rollers 5 coacting with the aforesaid rider rollers 3, respectively. Disposed above that intermediate roller 5 at the right, Fig. 1, is the ink-distributing roller 6, this being 5 the final roller of the series of ink-distributing rollers and said roller 6 coacting with the ink drum 4 as shown. Coactable with the rollers 5 and 6 is a rider roller 7.

As illustrated in Fig. 1, a series of ink-distributing rollers 8, 9, 10 are disposed above the ink drum 4, the roller 8 coacting with the aforesaid roller 6, the roller 9 coacting with the roller 8, and the roller 10 coacting with the roller 9. Coactable with the rollers 8 and 10 is a rider 15 roller 11.

The construction described above is conventional in the art. It will be understood that the various cylinders, the drum and the rollers are suitably journaled in the side frames F, F₁ of 20 the printing press and that these parts are operated in the manner well understood in the art. Further, the usual metal-to-rubber construction is illustrated in Fig. 4, the rollers 5, 6, for example, having rubber peripheries and the roller 7 25 and drum 4 having metal peripheries.

Suitably secured, as by bolts 12, Fig. 2, to horizontal surfaces of the respective side frame extensions f, f₁ is a supporting member 13 which extends transversely between said side frame extensions and comprises a pair of spaced, upstanding sections 13a, 13a to which are connected the respective web sections 13b. The supporting member 13 further comprises a section 13c disposed between the sections 13a, 13a, this section 35 13c serving as a support for a plate 14, said section 13c and the plate 14 being integrally formed or suitably secured together, as by screws 15. The plate 14 supports a blade 16 which is suitably secured thereto, as by the screws 17. The 40 length of the blade 16 is the same as the distance between interior surfaces of the aforesaid upstanding supporting member sections 13a, 13a. Coactable with the blade 16 are a plurality of screws 18 which are threaded through the aforesaid supporting member section 13c and which 45 coact with the lower surface of said blade 16.

The aforesaid upstanding supporting member sections 13a, 13a form bearings for the shaft ends or pintles 19 of the fountain roller 20 with which 50 the aforesaid blade 16 is coactable as hereinafter described. Loosely mounted on one shaft end 19 is a collar 21 having an arm 22 formed integrally therewith. Pivoted at 23 to this arm 22 is a connecting arm 24 terminating in an eccentric 55

strap 25 coactable with an eccentric 26 secured to and rotatable with one end of the shaft 4a of the aforesaid ink drum 4. Pivoted at 24a to the aforesaid arm 22 is a pawl 25a coactable with 5 a ratchet wheel 26 secured to and rotatable with the same shaft end 19 to which the aforesaid collar 21 is secured.

Each of the aforesaid frame extensions f , f_1 is provided with an open slot 21, these slots being 10 alined transversely of the machine. Adjacent each slot 21, a pair of inclined track members 28 are suitably secured to the adjacent frame extension, as by bolts 29, or equivalent, each pair of these track members forming an inclined track 15 for a slide 30, the tracks being inclined to the same extent. The slides 30 form bearings for the respective shaft ends or pintles 31 of an auxiliary roller 32, one shaft end 31 having secured thereto a gear wheel 32a adapted to mesh 20 with a gear wheel 33a secured to and rotatable with the adjacent shaft end 19.

Each slide 30 is threaded for the reception of a bolt 34 which is secured in fixed position by a lock nut 35, each bolt 34 terminating in a disk 25 36. These disks 36 are coactable, respectively, with eccentrics 37 secured to a horizontal shaft 38 rotatably mounted in the aforesaid frame extensions f , f_1 . At the exterior surface of the frame member F_1 , the shaft 38 carries a worm 30 wheel 39 which meshes with a worm 40 mounted on a stub shaft 41 rotatably mounted in the bifurcations of a bracket 42 suitable secured to the frame extension f_1 , as by the screws 43. The shaft 41, at its free end, carries a hand wheel 44 35 utilizable for adjustment purposes. Further, it is desirable for the shaft 41 to carry a circular collar 45 bearing a scale or index 46 coactable with a pointer 47 carried by the aforesaid bracket 43.

40 Suitably mounted in bearings in the aforesaid frame members F , F_1 is an oscillatory shaft 48 to which, adjacent the interior surface of each of said frame members F , F_1 , an upstanding arm 49 is secured, these arms 49 forming bearings for 45 the shaft ends or pintles 50 of a freely rotatable ink-transferring or ductor roller 51. Secured to the shaft 48 adjacent one end thereof is an arm 52 carrying at its free end a transversely disposed cam follower 53 coactable with a cam 54 50 secured to and rotatable with the aforesaid shaft 4a.

By adjustment of the screws 18, the end of the blade 16 is moved into the proper coacting relation with respect to the fountain roller 20 so that, 55 upon rotation of the latter, the ink is fed from the fountain in the proper manner so as to be on that surface of said fountain roller 20 which is exteriorly of the fountain. It will be understood that the fountain defined by the blade 16, 60 the sections 13a, 13a and the fountain roller 20 is otherwise liquid-tight so that ink from the body of ink I escapes from the fountain only along the edge of the blade 16.

Assuming that the parts are positioned as 65 shown in Fig. 5, the hand wheel 44 may be rotated to impart, through the disclosed gear arrangement, rotary movement to the shaft 38 whereby, under the control of the eccentrics 37, the respective slides 30 are moved in unison and 70 at the same speed along the inclined tracks provided therefor, respectively. In so doing, the gear wheel 32a is moved into meshing engagement with the gear wheel 33a, and the auxiliary roller 32 is moved into engagement with the fountain 75 roller 20.

When the printing press is placed in operation, rotation imparted to the shaft 4a causes cyclic movement of the connecting arm 24 under control of the eccentric 26 whereby the arm 22 is oscillated to produce, through the pawl 25a and ratchet wheel 26, step-by-step rotative movement of the fountain roller 20 in a counter-clockwise direction, Fig. 1. By reason of the mechanical connection provided by the gear wheels 33a and 32a, the auxiliary roller 32 is rotated step-by-step 10 in synchronism with the rotative movement of the roller 20. When the fountain roller 20 is rotated as described immediately above, a coating of ink is spread on the surface area thereof as the latter recedes step-by-step from the edge of the 15 blade 16 and, as will clearly appear, the ink thus spread on said fountain roller 20 is transferred to the surface of the auxiliary roller 32.

As the parts are shown in Fig. 1, the ductor roller 51 is positively held in engagement with the ink-distributing roller 10. This condition exists by reason of the fact that the high surface of the cam 54 is in engagement with the cam follower 53 at this time. As rotative movement of the shaft 4a continues, the high surface of the cam 54 recedes from the cam follower 53 and is replaced by the low surface of said cam 54. When this happens, the ductor roller 51 swings under the influence of gravity or by spring action in a counter-clockwise direction, Fig. 1, until the surface thereof comes into engagement with the surface of the auxiliary roller 32. While the two rollers last named are in engagement, rotation of the auxiliary roller 32 is effected as described above and, as a result, some rotative movement 35 is imparted to the ductor roller 51 which, accordingly, takes up a charge of ink. As soon as the high surface of the cam 54 again engages the cam follower 53, the ductor roller is swung to the position shown in Fig. 1 where it again engages the ink-distributing roller 10 with resultant transfer of a supply of ink thereto. 40

It will be understood that the operations involving the rollers 20, 32 and 51 as described above may and preferably do occur in the same 45 rapid sequence as exemplified, for example, in the prior art movements of fountain and ductor rollers. Accordingly, individual charges of ink are transferred at a rapid rate to the ink-distributing roller 10 from which the ink is transferred in the usual way to the plate cylinder 1 and thence to the blanket cylinder. 50

The above described oscillatory movement of the ductor roller 51 is well known to the art when such movement occurs between an ink-distributing roller, such as the roller 10 and a fountain roller, such as the roller 20. However, by my invention as described above, the ductor roller 10 oscillates between an ink-distributing roller 10 and the auxiliary roller 32. By virtue of the 60 provision of such an arrangement, a number of important and novel advantages accrue.

Thus, as disclosed in Figs. 1 and 4, the auxiliary roller 32 is geared to the fountain roller 20 so that movement of the fountain roller 20 is transmitted to the auxiliary roller 32. Preferably, although not necessarily, the gear arrangement is such that the auxiliary roller 32 is rotated faster, for example, twice as fast more or less, than the fountain roller 20. It results, therefore, that relative movement between the two rollers 20 and 32 occurs while both of said rollers are rotating. As a result, there is a grinding or 70 analogous action on the ink between the engaging roller surfaces with the result that the ink 75

is rendered more smooth with elimination of undissolved particles. This, obviously, is a distinct advantage as regards improvement of the printed products.

5 In addition, the ink adhering to the surface of the auxiliary roller 32 is thinner, i. e., more spreading has occurred, than occurs with respect to the ink on that surface of the fountain roller 20 exteriorly of the fountain. This beneficial result arises primarily by reason of the higher peripheral speed of the auxiliary roller 32 compared to the fountain roller 20.

In connection with the foregoing description, it was stated that the hand wheel 44 could be manipulated to a desired extent so as to bring the auxiliary roller 32 into contacting relation with the fountain roller 20. Obviously, the coupling thus effected may be either close or loose as desired. By a reading taken from the index 20 46 and pointer 47, the same coupling may be obtained with accuracy at any subsequent time. Therefore, even though the adjustment between the fountain roller 20 and the auxiliary roller 32 is necessarily changed as may be required for 25 cleaning purposes, for example, the previous degree of adjustment may readily be obtained by reestablishing a previous index-pointer reading. This is advantageous because insuring substantial uniformity as regards appearance between jobs 30 printed at different times.

Another important feature of my invention relates to the fact that the adjusting arrangement for the auxiliary roller 32 is so constructed and arranged that said auxiliary roller 32 together with the gear wheel 32a therefor may be moved to idle position with respect to the fountain roller 20 and the gear wheel 33a, Fig. 7. When this adjustment has been completed, the ductor roller 51 may oscillate between the fountain roller 20 and the ink-distributing roller 10 free from any contact with the auxiliary roller 32. This construction is advantageous in case the operator should desire to operate the printing press in the usual manner as well known in 45 the art.

In view of the fact that the "throw" of the ductor roller 51 is necessarily different if either the fountain roller 20 or the auxiliary roller 32 is to be engaged as desired, Figs. 7 and 6, it follows that the low surface of the cam 54 should be sufficiently "low" so that the cam follower 53 does not engage therewith for either position of the ductor roller 51 as shown in Figs. 6 and 7.

As shown on the drawings, the auxiliary roller 55 32 should be formed from metal the same as the fountain roller 20. Under such circumstances, there is a rubber-to-metal contact between the ductor roller and either of the rollers first named.

The arrangement of my invention is readily 60 applicable to any type of printing press as mentioned herein and, among such presses, for example, is the improved Rutherford metal decorating press. It will be understood that the material to be printed upon or decorated may 65 be paper, metal or otherwise as desired. In all cases, by my invention, improved ink distribution is obtained on the final product with marked elimination of the streaks found in prior art products. Further, as stated, the uniformity of 70 appearance on jobs printed at different times may be preserved to a marked degree.

While the invention has been described with respect to a certain particular preferred example which gives satisfactory results, it will be understood by those skilled in the art after under-

standing the invention, that various changes and modifications may be made without departing from the spirit and scope of the invention as set out in the claims.

What is claimed as new and desired to be secured by Letters Patent is:

1. In a printing press, the combination with a fountain roller, and means for imparting step-by-step rotative movement to said fountain roller, of an ink-distributing roller, a ductor roller for 10 periodically transferring ink to said ink-distributing roller, an auxiliary roller for transferring ink from said fountain roller to said ductor roller, and means independent of the exterior surface of said fountain roller for imparting rotative 15 movement to said auxiliary roller.

2. In a printing press, the combination with a fountain roller, and means for imparting step-by-step rotative movement to said fountain roller, of an ink distributing roller, a ductor roller for 20 periodically transferring ink to said ink-distributing roller, an auxiliary roller for transferring ink from said fountain roller to said ductor roller, and means controlled by said fountain roller for 25 imparting step-by-step rotative movement to said auxiliary roller.

3. In a printing press, the combination with a fountain roller, and means for imparting step-by-step rotative movement to said fountain roller, of an ink-distributing roller, a ductor roller for 30 periodically transferring ink to said ink-distributing roller, an auxiliary roller for transferring ink from said fountain roller to said ductor roller, and means controlled by said fountain roller for imparting step-by-step rotative movement to said 35 auxiliary roller, said auxiliary roller being rotated substantially faster than said fountain roller.

4. In a printing press, the combination with a fountain roller, of an ink-distributing roller, a 40 ductor roller periodically engageable first with said fountain roller and then with said ink-distributing roller, an auxiliary roller disposed adjacent said fountain roller in suitable spaced relation with respect thereto, and means for 45 moving said auxiliary roller into engagement with said fountain roller, said auxiliary roller, when positioned as last described, being periodically engaged by said ductor roller and said auxiliary roller, when thus positioned, preventing engagement of 50 said ductor roller with said fountain roller.

5. In a printing press, a fountain roller, an ink-distributing roller, a ductor roller for periodically transferring ink from said fountain roller 55 to said ink-distributing roller, an auxiliary roller, and precision means for adjusting said auxiliary roller toward and into contact with said fountain roller, said auxiliary roller, when positioned as last described, being periodically engaged by said ductor roller and said auxiliary roller, when thus positioned, preventing engagement of said ductor roller with said fountain roller.

6. In a printing press, a fountain roller, an ink-distributing roller, a ductor roller for periodically transferring ink from said fountain roller to said ink-distributing roller, an auxiliary roller, and precision means for adjusting said auxiliary roller toward and into contact with said fountain roller, said auxiliary roller, when positioned as 70 last described, being periodically engaged by said ductor roller and said auxiliary roller, when thus positioned, preventing engagement of said ductor roller with said fountain roller, said precision means comprising eccentrics engageable, respec- 75

- tively, with opposite ends of the shaft for said auxiliary roller, said precision means further comprising mechanism for operating said eccentrics in unison.
7. In a printing press, a fountain roller, an ink-distributing roller, a ductor roller for periodically transferring ink from said fountain roller to said ink-distributing roller, an auxiliary roller, and precision means for adjusting said auxiliary roller toward and into contact with said fountain roller, said auxiliary roller, when positioned as last described, being periodically engaged by said ductor roller and said auxiliary roller, when thus positioned, preventing engagement of said ductor roller with said fountain roller, said precision means comprising eccentrics engageable, respectively, with opposite ends of the shaft for said auxiliary roller, said precision means further comprising mechanism for operating said eccentrics in unison, said mechanism comprising a shaft and worm and worm wheel mechanism for rotating said shaft.
8. In a printing press, a fountain roller, an ink-distributing roller, a ductor roller for periodically transferring ink to said ink-distributing roller, an auxiliary roller for transferring ink from said fountain roller to said ductor roller, and means for moving said auxiliary roller from a position where it is spaced from said fountain roller to another position where it is in engagement with said fountain roller.
9. In a printing press, the combination with a fountain roller, and means for imparting rotative movement to said fountain roller, of an ink-distributing roller, a ductor roller for periodically transferring ink to said ink-distributing roller, an auxiliary roller for transferring ink from said fountain roller to said ductor roller, and means for rotating said auxiliary roller at a different rate of speed than the speed of rotation of said fountain roller.

WILLIAM N. MISURACA.

20
